UNITED STATES PATENT OFFICE

2,136,966

MANUFACTURE OF QUINONE

Alwin C. Carus, La Salle, Ill., assignor to Carus Chemical Company, Inc., a corporation of Illinois

Application September 25, 1936, Serial No. 102,609

3 Claims. (Cl. 202—46)

This method relates to the manufacture of quinone and other like substances in which the product is distilled from a reaction mass with steam.

5 The distillation of quinone and other organic bodies by steam distillation has long been practiced, but in the preparation of quinone and certain other organic materials by steam there is a tendency for the quinone to 10 dense and form a cake in the condenser which effectively blocks the distillation operation.

It has now been discovered that this difficulty 15 may be overcome providing the concentration of the quinone in the water condensate is kept below saturation, and preferably well below saturation to such an extent that no cake is formed. This result may be accomplished by condensing the steam in an excess of water which is constantly refreshed, followed by subsequent removal of the quinone from this water. From the 20 standpoint of economy, however, it is preferred to recirculate the water, and this is particularly true because it is impossible to completely remove the quinone therefrom. Preferably, this 25 result is accomplished by removing the water before it has become concentrated or saturated with quinone and removing the quinone, or some of it, from the water by contact with a water immiscible quinone solvent, separating the water 30 therefrom and returning it to the condenser.

As an example of this invention, quinone is distilled from a reaction mixture by the use of steam and preferably under a vacuum, for example, such as to produce a temperature of the 35 order of 60 to 80° C. and the distillate condensed in water from which the quinone is removed with a quinone solvent so that the quinone content of the water is kept so low that there will be no blocking of the condenser and no cake will be 40 formed on the pipe leading into the water.

This result may be accomplished by discharging the quinone vapors beneath a body of water which is then circulated rapidly into another chamber and then passing it through or in contact with a solvent, and returned to the condensing vessel.

The rapidity of circulation and the volume of water are, of course, adjusted so that caking is entirely or substantially prevented. These 45 adjustments will, of course, also depend upon the solubility of quinone in the solvent.

The invention is illustrated diagrammatically in the drawing, in which 1 represents a still containing a reaction mixture 2 into which steam 50 may be supplied by the line 3. The reaction mix-

ture may be such as is obtained by oxidizing aniline with manganese compounds. Distillate passes off through the line 4 into the condenser 5, the mouth 6 of the line 4 being within the body of water 7 in the condenser. The water is 5 circulated through the line 12 by the pump 13 into the extraction vessel 15, wherein a layer of solvent is maintained. A cooling coil 16 may be supplied therein for cooling the solvent. The arrangement shown is for a solvent heavier than 10 water, but where a lighter solvent is used the flow may be reversed. The washed water passes through the line 17 controlled by the valve 18 and back to the condenser 5.

A vacuum is maintained within the condenser 15 5 by the pump 10, both for the purpose of facilitating the evaporation of quinone in the still and also to cool the water within the condenser by boiling. The boiled water is condensed within the reflux condenser 19. A line 20, controlled by 20 valve 21, may lead from the solvent vessel 14 to the condenser tubes and may be employed to wash out the condenser of quinone, if necessary, by circulating some of the washed water therethrough. The valves 18 and 21 may be kept 25 partially open, if desired, to maintain a higher pressure in the vessel 14 than in the condenser 5.

This system has the advantage that the solvent need not be subjected to a high vacuum under which it would evaporate and be lost, or would 30 have to be recovered in part through an expensive recovery system. A low boiling solvent is desirable in the subsequent recovery of the quinone. The chamber 15 may even be under pressure if desired. Thus, very low boiling solvents may be employed. 35

The water in the condenser 5 should be kept 40 slightly acid to prevent decomposition of quinone. The water may be cooled by vacuum induced evaporation.

Any water immiscible solvent may be employed, but preferably it should be one having a high vapor pressure wherever heat or a high vacuum is employed.

The quinone may then be recovered readily 45 from the solvent and the water.

The invention is, of course, applicable to any other compound, organic or inorganic, which has a tendency to cake in the condenser, and 50 which is volatile with steam.

The foregoing detailed description has been given for clearness of understanding only and no unnecessary limitations should be understood therefrom, but the appended claims should be 55

construed as broadly as permissible in view of the prior art.

I claim:

1. The method of distilling a quinone which comprises volatilizing the quinone with steam, condensing the vapors in a body of water in the substantial absence of an organic solvent for the quinone, and continuously extracting the quinone from the water by circulation of the water through a body of solvent to maintain the

concentration of the quinone therein at a point so low that it will not form a cake in the condenser.

2. The method as set forth in claim 1, in which the water is cooled by maintenance of a 5 vacuum thereon.

3. The method as set forth in claim 1 in which the quinone is benzoquinone.
